UNITED STATES PATENT OFFICE

119,694

DESIGN FOR A DRESS ENSEMBLE

Leo Beilinson, New York, N. Y.

Application February 23, 1940, Serial No. 90,431

Term of patent 3½ years

To all whom it may concern:

Be it known that I, Leo Beilinson, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary front view of the dress member.

Fig. 4 is a rear view of Fig. 3.

Fig. 5 is a plan view of one of the detachable panels of the jacket member as shown in Fig. 1.

The characteristic feature of my design resides in the combination on the specific dress ensemble disclosed of the specific detachable panels on the jacket member as shown.

I claim:

The ornamental design for a dress ensemble, substantially as shown and described.

LEO BEILINSON.
